US00D849960S

(12) **United States Design Patent** (10) **Patent No.:** **US D849,960 S**
(45) **Date of Patent:** **** May 28, 2019**

(54) **MASSAGING TOOL**

(71) Applicant: **amane factory inc.**, Tokyo (JP)

(72) Inventors: **Yoshitake Saito**, Tokyo (JP); **Jun Tanimoto**, Tokyo (JP); **Hiroaki Tanno**, Tokyo (JP); **Shingo Mori**, Tokyo (JP)

(73) Assignee: **AMANE FACTORY INC.**, Tokyo (JP)

(**) Term: **15 Years**

(21) Appl. No.: **29/637,543**

(22) Filed: **Feb. 20, 2018**

(30) **Foreign Application Priority Data**

Dec. 18, 2017 (JP) 2017-028212

(51) **LOC (11) Cl.** **28-03**

(52) **U.S. Cl.**

USPC **D24/211**

(58) **Field of Classification Search**

USPC ..... 119/702, 707; 446/220-226, 227, 400, 446/431, 486; 473/569-575, 576-580, 473/581-585, 586-591, 592-597, 473/598-603; D11/125, 48; D21/662, D21/678, 680, 707-714, 716, 788; D30/160; 482/91, 93, 105, 122, 148; 601/15, 18, 19, 27, 28-32, 46, 47, 48, 52, 601/99, 112, 113, 118, 122, 125, 129, 601/135, 137, DIG. 12, DIG. 14-DIG. 17; D24/133, 200, 211-215; 600/38, 39, 40, 600/41

(57) **CLAIM**

The ornamental design of a massaging tool, as shown and described.

DESCRIPTION

FIG. 1 is a front view of the massaging tool showing our new design.

FIG. 2 is a rear view thereof.

FIG. 3 is a right side view thereof.

FIG. 4 is a left side view thereof.

FIG. 5 is a top view thereof.

FIG. 6 is a bottom view thereof.

FIG. 7 is a perspective view thereof; and,

FIG. 8 is another perspective view thereof.

1 Claim, 4 Drawing Sheets
